UNITED STATES PATENT OFFICE

SAMUEL W. LUITWIELER, OF LOS ANGELES, CALIFORNIA

COMPRESSOR

Application filed July 28, 1927. Serial No. 208,969.

My invention is a compressor suitable for compressing gases in connection with refrigerating machines.

An object of my invention is the construction of a compressor for compressing gases and vapors from refrigerating machines to condense these into a liquid, and to provide a type of compressor which will operate without vibration and substantially noiselessly. My compressor is particularly adapted for use with household refrigerating machines where the vibration of the compressor is disagreeable.

Another object of my invention is a compressor of a double stroke type having a pair of pistons in alignment, these being operated by a cam mounted on a power shaft.

In constructing my invention I utilize a frame with a casing in which is mounted a cam on the power shaft. A pair of aligned pistons have a connecting yoke which, by means of rollers, is operated by the cam. Each of the pistons has an opening at the base to allow passage of the gases and has a valve at its outer end, this valve being spring seated, the valve closing on the compression stroke of the piston and driving the compressed gases out of the discharge pipes into a tank, the discharge pipes having check valves.

My invention may be more readily understood from the following description and drawings, in which:

Figure 1 is partial end elevation and partial central section.

Figure 2 is a half side elevation partly broken away, and half central vertical section.

Figure 3 is a vertical transverse section through one of the cylinders and its piston on the line 3-3 of Fig. 2 in the direction of the arrows.

Figure 4 is a side elevation showing the assembly of my compressor with an electric motor.

Figure 5 is a part central horizontal section with one of the pistons being shown in plan.

In constructing my invention I have a suitable frame 11 mounted on a base 12, this frame

having side walls 13 connected by end walls 14, one of the side walls 13 being provided with a cover plate 15. This forms a chamber 16 to accommodate the cam and the common yoke, as hereunder set forth. Each end of 55 the casing is provided with a flange 17 to each of which is bolted a cylinder 18, the cylinders being provided with heat radiating fins 19. Each of the cylinders is provided with a head 20 bolted thereon, each head 66 having a discharge passage 21 connected to an outlet passage 22, there being a check valve 23 seated in each outlet passage and pressed into position by a spring 24 which bears against a cage 25. The compressed gases are 65 carried by pipes 26 to a common receiving tank 27 which is removably held in the frame 11 by set screws 27'.

The drive shaft 28 is mounted in suitable journals 29 and 30 in the back wall 13 and 70 the cover plate 15, respectively, there being suitable bushings, and a packing 31 and 32 is used on the side of the shaft passing through the back wall, there being a suitable gland nut 33. The other end of the shaft is enclosed by a cover nut 34. The shaft has a pulley 35 thereon which is driven by a belt 36 from the electric motor 37.

The pistons 38 having oil grooves 38' are connected by a common yoke 39, this yoke 80 having a vertical slot 40 therein to accommodate the cam, as hereunder mentioned, and horizontal slots 41 on opposite sides to accommodate the drive shaft 28. There is a gas intake 42 into the chamber 16; and 85 a port 43 leads into a chamber 44 in each of the pistons through the base thereof.

Each piston has a plug 45 screw-threaded into its outer end, each of these plugs having passages 46 therethrough and having a valve seat 47 at the outer end on which is seated a valve 48. There is preferably a clearance space 49 in each of the cylinder heads 20. The valves are provided with valve stems 50 90 slidable through the plugs, and have washers 51 secured at the ends with compression springs 52 acting between the washers and the plugs, thus normally holding the valves seated.

The common yoke 39 is provided with studs 100

53 on which are mounted rollers 54, these rollers being in the vertical slot 40, and the studs 53 being mounted at both ends in the yoke 39 upon opposite sides of the slot 40. 5 These are engaged by the cam 55 which is keyed or otherwise secured to the power shaft 28. In order to lighten the cam there are 10 cutout parts 56.

The manner of operation and functioning 10 of my compressor is substantially as follows:

As above mentioned, this compressor is particularly adapted for use with household refrigerating machines and is adapted to compress carbon dioxide, sulphur dioxide or 15 ammonia gases, these gases being compressed and condensed in the tank 27. The intake gases from the refrigerating machine are drawn into the chamber 16 through the inlet opening 42 and when a piston is being 20 drawn out of its cylinder into the chamber 16, the gases pass through the ports 43, and due to the fact that the gases have a pressure sufficient to compress the springs 52 seating the 25 valves 48, the gases are forced through such valves, the valves raising slightly from their seats. The partial vacuum caused by the drawing of the piston from its cylinder causes the spaces between the piston and the cylinder head to be filled with the gases, for, on account 30 of the check valve 23, none of the gases can be withdrawn from the tank 27. On the compression stroke, that is, when each piston is being forced into its cylinder, the valve 38 is seated and thus forces the gas through 35 the passage 21 and the outlet 22 opening the check valve 23. The gas then flows through the pipes 26 into the receiving tank 27.

It will be noted, especially by observation of Fig. 2, that the cam 55 is constructed in 40 such a manner that those portions of the cam face intercepted by the plane including the axis of rotation of the shaft 28 and the center of the cam 55, are of greater radius of curvature than the mean radius of curvature 45 of the remaining portions of the cam surface, i. e., these specified portions of the cam surface are more nearly flat than the other portions, with the result that when the rollers 54 are traversing these specified portions of the cam surface, the motion of the connecting rod 39 and its pistons 38, is at its lowest 50 velocity. Since these portions of greatest radius of curvature are in the line of eccentricity of the cam, the periods of minimum 55 acceleration of the rod and pistons, occur while the pistons are at the ends of their stroke, with the result that the acceleration of the pistons at the end of their stroke is considerably less than with a crank type of action. In other words, the pistons are brought to rest more gradually and start their return motion more gradually than with the crank type of action, thus adding materially to the 60 avoidance of vibration, and hence, decreasing 65

noise caused by the operative parts of the compressor.

It is to be further noted that although the cam has been flattened as above described, upon two opposite sides, the diameter of the cam when measured through the axis of rotation of the shaft 28, is constant throughout the entire periphery of the cam and substantially equal to the distance between the proximal faces of the rollers 54, with the result that play between the cam and yoke is minimized.

Various changes may be made in the principles of my invention without departing from the spirit thereof, as set forth in the 80 description, drawings and claims.

I claim:

1. A compressor comprising in combination a frame having a back wall, forwardly extending walls therefrom and a removable cover plate forming a chamber, a shaft journaled in the back wall and the cover plate and having a cam thereon in the chamber, a pair of cylinders secured to the opposite sides of the forwardly extending walls, heads secured to said cylinders, pistons slidable in the cylinders being connected by a common yoke, interengaging means between the yoke and the said cam, an inlet to the chamber, the pistons having ports connecting to the chamber, check valves in the pistons, a removable tank secured in the said frame, and discharge outlets from the cylinder heads to the said tank, said discharge having check valves.

2. A compressor comprising in combination a casing, a shaft journaled therein, a cam carried by said shaft, those portions of the face of the cam intercepted by the plane including the centers of the shaft and cam being of greater radius of curvature than the mean radius of curvature of the remainder of the cam surface, axially aligned cylinders at opposite sides of said casing, pistons reciprocable within said cylinders, a common yoke rigid with said pistons and having a horizontal slot for the reception of said shaft and a vertical slot for the reception of said cam, a stud extending across said vertical slot adjacent each end thereof, a roller revolvably mounted upon each stud and in engagement with said cam, means for admitting fluid to said cylinders, and means for conducting fluid away from said cylinders.

3. In a pump, a pair of axially aligned cylinders, a shaft journaled for rotation between the cylinders and perpendicular to the common axis thereof, a piston reciprocable in each cylinder, a common yoke rigid with both pistons, a cam rigidly and eccentrically mounted upon said shaft, a pair of rollers revolvably mounted upon said yoke in position to simultaneously engage opposite sides of said cam, those portions of the face of the cam intercepted by the plane including the centers of the shaft and cam being of greater 125

radius of curvature than the mean radius of curvature of the remainder of the cam surface.

4. In a pump, a pair of axially aligned cylinders, a shaft journalled for rotation between the cylinders and perpendicular to the common axis thereof, a piston reciprocable in each cylinder, a common yoke rigid with both pistons, a cam rigidly and eccentrically mounted upon said shaft, a pair of rollers revolvably mounted upon said yoke in position to simultaneously engage opposite sides of said cam, those portions of the face of the cam intercepted by the plane including the centers of the shaft and cam being of greater radius of curvature than the mean radius of curvature of the remainder of the cam surface, and the diameter of the cam measured through the center of the shaft being constant throughout the entire periphery of the cam.

In testimony whereof I have signed my name to this specification.

SAMUEL W. LUITWIELER.
